UNITED STATES PATENT OFFICE.

RICHARD H. S. THOMPSON, OF NEW YORK, N. Y.

ELECTRIC PRIMER.

SPECIFICATION forming part of Letters Patent No. 323,974, dated August 11, 1885.

Application filed November 28, 1884. (No model.)

To all whom it may concern:

Be it known that I, RICHARD H. S. THOMPSON, a citizen of the United States, residing in the city, county, and State of New York, 5 have invented certain new and useful Improvements in Electric Cartridges, of which the following is a specification.

My invention relates to cartridges, and more especially those used in fire-arms wherein electricity is used as a means for igniting the explosive material; and it has for its object to render such cartridges less expensive and more certain of action; and to these ends my invention consists in an electrical primer for 15 cartridges constructed as more particularly pointed out hereinafter, and adapted to be fitted into the central depression or recess of the cartridge and to be removed for further use.

Heretofore cartridges have been supplied 20 with means for igniting the explosive, but these have been formed as a part of the cartridge itself, and were cumbersome and expensive, and generally open to other objections—such as requiring the cartridge to be placed in 25 the gun in a certain specified relation so as to bring the electrodes in proper position. My invention overcomes these objections and enables the use of the ordinary form of cartridge now on the market, the primer being adapted 30 to be applied to the recess in the end for the reception of the usual fulminate, thereby saving the expense of new machinery to form a cartridge of this character. The cartridges may be reloaded as long as they withstand 35 the wear and tear of the explosive, and then the primer may be removed and applied to other cartridge cases. The electric primer may be made in various ways in carrying out 40 my invention, as will be manifest; and I have further improved such cartridge by so arranging the electrodes that the cartridge may be inserted in the gun-barrel in any position and still be adapted to make connection with 45 the electrodes of the conductors leading from the source of electric energy.

My cartridge is adapted for use more especially in my improved electric gun, described and claimed by me in my application No. 104,760, filed August 23, 1883, but it may of 50 course be used in any electric fire-arm.

Referring to the accompanying drawings for a more particular description of my invention,

Figure 1 is a perspective view of a cartridge containing one form of my improved primers. Fig. 2 is a section of the same. Fig. 3 is an 55 end view. Fig. 4 is an enlarged section showing the primer removed. Figs. 5, 6, 7, 8, and 9 are views showing modified forms of primer.

The cartridge shell or case A may be of metal, paper having a metal end, or any other 60 convenient construction, and in place of the usual fulminate the recess a serves as a holder for the electric primer B. The body of the primer may be made of any suitable non-conducting material, and may have a mass of 65 fulminating material, b, on its end, in which the terminals of the conductors are embedded at a proper distance apart, as shown in Fig. 4, as when the secondary spark is used to ignite the explosive, or a conductor of high 70 resistance may be embedded therein, as shown in Fig. 6, when the ignition is caused by the heated or incandescent conductor. In some cases the fulminate is not applied to the igniter, but may be placed inside the cartridge in any 75 suitable manner, or the powder or other charge may be placed directly in contact with the conductor.

In Fig. 8 the igniter B is shown as having two conductors passing through it, each arranged eccentrically with the exterior terminals, c c, flattened or expanded, and extended partially around the surface of the non-conducting body of the igniter, so that the electrodes may come in contact with the respective terminals, no matter what the position of the cartridge.

In Fig. 9 another, and perhaps preferable, form of igniter is shown, wherein but a single conductor, d, passes through the body of the igniter, and this is arranged in the center thereof, the other terminal, e, passing up the side of the non-conducting body and making contact with the metallic body of the shell or case around the opening or recess. In this arrangement the central terminal of the conductor is always in the center of the cartridge, and a single moving electrode connected to the electric source need be used, the other terminal being connected to the breech-block or 100 other part of the gun which is in contact with the metal of the cartridge-case, and thereby completing the electric circuit through the igniter.

I prefer to make the primer tapering toward its forward end so that it will not only fit firmly and securely in the recess of the cartridge, but will be prevented from being forced 5 too far therein by the firing-pin impinging against it. The electrodes may also be made tapering, or otherwise so formed as to attain the same end.

The insulating material may be of any suitable kind, and may be put in the recess in a plastic state, hardening afterward.

Other modifications of my igniter are apparent to those skilled in the art, and I wish it to be understood that I do not wish to be 15 limited to the precise details of construction shown.

From the above it will be seen that the gist of my present invention consists in making a 20 separate and removable igniter, adapted to the ordinary forms of cartridge-case, that can be manufactured as articles of trade, and applied much the same as when an ordinary percussion-cap or other mechanical igniter is used.

Having now described my invention, what 25 I claim is—

1. As a new article of manufacture, an electrical igniter for cartridges, consisting of a non-conducting body, and a conductor em-

bedded therein and arranged to make contact with the firing electrodes, the igniter being 30 constructed to be applied to and removed from the priming recess of an ordinary cartridge, substantially as described.

2. An electrical igniter, consisting of a body of non-conducting material, having electric conductors embedded therein, and having a recess in its forward end containing the explosive or fulminate, the whole being adapted to fit the priming recess of an ordinary cartridge, substantially as described. 35

3. An electrical igniter for cartridges, consisting of a body of non-conducting material, electric conductors embedded in such material, the outer ends of the conductors being bent and curved, as described, and a mass 40 of fulminating material held in a recess in the front of the igniter, in which the forward parts of the conductors are embedded, substantially as described.

In testimony whereof I have signed my 50 name to this specification in the presence of two subscribing witnesses.

RICHARD H. S. THOMPSON.
